Frank Eshleman I Park Althouse
Ward M. Burkhardt

UNITED STATES PATENT OFFICE.

ISAAC PARK ALTHOUSE, OF QUARRYVILLE, PENNSYLVANIA.

RAILWAY-RAIL, FASTENING.

1,053,264.

Specification of Letters Patent.

Patented Feb. 18, 1913.

Application filed October 31, 1911. Serial No. 657,833.

To all whom it may concern:

Be it known that I, ISAAC PARK ALTHOUSE, a citizen of the United States, residing at Quarryville, in the county of Lancaster and State of Pennsylvania, have invented new and useful Improvements in Railway-Rail Fastenings, of which the following is a specification.

My invention relates to means for securing railroad rails and ties to each other, and the object thereof is to produce a device of said character adapted to prevent the spreading of the rails.

A further object thereof is to secure the rails from slipping laterally on the ties, and a still further object of my invention is to produce a more simple, cheap and efficient device of said class than has heretofore been produced.

In the accompanying drawings in which like reference characters indicate similar parts, Figure 1 is a ground plan view of my invention, Fig. 2 is a side elevation of the same, and Fig. 3 is a transverse or end elevation showing the tie in cross section.

My invention includes, generally, a pair of side plates adapted to be clamped upon a railroad tie on each of which is seated the rail, a plurality of screw threaded studs on the upper face of the side plates on both sides of the rail seat, a buttress plate secured on each of the side plates adapted to bear against the outer faces of the base and web and tread of the rails, and a cross brace having T-ends adapted to bear against the inner faces of the base and web of the rails and secured upon the upper faces of the side plates, and other details of construction to be hereinafter more fully described and set forth.

Referring now to the drawings, 1 indicates a railroad tie of ordinary form. Adjacent to each end of the tie are secured thereon the side plates 2, having the depending ends 3 which embrace the sides of the tie and on which are provided the depending screw threaded lugs 4 adapted to register with slots in the ends of the yokes 6 which embrace the lower face and part of the sides of the tie by being secured by the nuts 7.

Upon the upper face of each side plate 2 are two pairs or sets of vertically projecting threaded studs 8 and 9, the studs 8 being

outside the rail seat and the studs 9 being 55 inside thereof or between the two rails carried on the tie.

For the purpose of preventing the spreading of the rails, I provide buttresses 10 on the outer side of each rail 11 secured upon 60 the side plates 2. Said buttresses comprise the plates 12, pierced to register with the studs 8, and held thereon by the nuts 13. The inner edge 14 of each plate is adapted to bear against the web of the rail and the 65 lower face is beveled at 15 to bear upon the top of the base, and the shoulder 16 engages the edge of the base as shown. Upon the top faces of the plates 12 and between the orifices therein, I provide a projecting 70 shoulder 17, preferably integral with the plate adapted to bear upon the outer face of the web of the rail and the under face of the tread to support the rail in upright position.

For the purpose of maintaining the proper gage between the rails, and for locking the side plates together, I provide the cross bar 18, which, as shown, is provided with T-plates 19 at each end, which are suitably 80 beveled and shaped to bear upon the top and edge of the bases on the inner sides of the rails. Said T-plates are provided with spaced orifices to register with the studs 9 on the side plates and are secured thereon 85 by the nuts 20.

From the foregoing description, and by reference to the accompanying drawings, it will be apparent that the rails are carried upon side plates clamped upon the ties; that 90 they are supported and secured against lateral displacement by the buttress plates secured upon the side plates; that they are supported and secured at the proper gage by the intermediate cross bar, and that the 95 opposite side plates bearing on the rails are locked together by the said cross bar to support and prevent shifting in either direction.

I claim:

The combination with side plates clamped 100 upon a railroad tie adjacent to its ends, a rail seat upon each side plate and studs upon each side of said seats, yokes embracing the lower face of the tie for securing said plates thereon, clamping plates and buttresses removably secured upon said side plates, comprising clamps on the outer sides of the rails adapted to clamp the base of

the rail and bear against the outer face of the web and the under face of the tread thereof, and a cross bar between the rails having T-shaped ends provided with orifices adapted to register with the studs on the side plates on the inner side of the rails, adapted to clamp the base and bear against the web of each rail, substantially as described.

I. PARK ALTHOUSE.
